UNITED STATES PATENT OFFICE.

GEORGE H. S. MOYES, OF PITTSBURGH, PENNSYLVANIA.

DETACHABLE RIM FOR VEHICLE-WHEELS.

1,182,925.

Specification of Letters Patent. Patented May 16, 1916.

Application filed May 22, 1915. Serial No. 29,880.

To all whom it may concern:

Be it known that I, GEORGE H. S. MOYES, a citizen of the United States, and resident of Pittsburgh, in the county of Allegheny and State of Pennsylvania, have invented a new and useful Improvement in Detachable Rims for Vehicle-Wheels; and I do hereby declare the following to be a full, clear, and exact description thereof.

10 My invention relates to detachable-rims for vehicle-wheels.

The object of my invention is to provide a simple form of detachable-rim adapted to be readily and quickly adjusted in position 15 or removed without the labor and difficulty required in the adjustment and removal of the detachable-rims now ordinarily employed.

To these ends my invention comprises the 20 novel features hereinafter set forth and claimed.

In the accompanying drawings, Figure 1 is a view of a portion of a wheel showing my invention applied thereto; Fig. 2 is an 25 enlarged section on the line 2—2, Fig. 1; Fig. 3 is a perspective view of a portion of the felly-band; Fig. 4 is a perspective view of a portion of the tire-carrying-rim; Fig. 5 is a perspective view of a portion of the 30 locking-ring; Fig. 6 is a section on the line 6—6, Fig. 4; Fig. 7 is a perspective view of the locking-plate; and Fig. 8 is a view of a portion of the wheel showing the tool 35 in place for shifting the locking-ring.

Referring to the drawings, the numeral 1 indicates the felly; 2 the felly-band fitting around the felly. This felly-band is provided with the studs 3. A flange 4 is adapted to be engaged by the inner half of the 40 tire-rim 5.

The numeral 6 designates the valve-opening.

The felly has the ratchet-plate 7 inserted therein and held in place by the screws 8 45 which project therefrom for the purpose fully hereinafter set forth.

The tire-rim 5 is made in two sections, divided along the line 9, and these sections are locked together by the locking-ring 10, 50 said locking-ring consisting of a split spring-ring having the flanges 11, which engage the ribs 12 on the inner face of the tire-rim 5. When the locking-ring 10 has been adjusted in position with its flanges 55 11 engaging the ribs 12 of the tire-rim, the ring is expanded and an insert-block 13 is

interposed between the ends of the locking-ring, said block being secured in place by the screw 14, as clearly indicated in Figs. 4 and 6. The ends of the ring are beveled as 6 at 10^a, and the edges of the block 13 are also beveled to engage therewith. By making the tire-rim in two halves, it is apparent that the tire may be slipped over one half, and then the other half inserted, thereby 65 doing away with the necessity of expanding the tire to get it over the flanges 15 of the tire-rim. In removing the tire, it is only necessary to remove the locking-ring 10, whereby the tire-rim sections can be 70 separated and the tire quickly removed. The rim sections overlap each other as indicated at 16. In order to bring the valve opening in the tire-rim 5 into register with the valve opening 6 of the felly-band, 2, the 75 tire-rim has the notch 17, which is adapted to engage the lug 18 on the felly-band. The felly-rim carrying the tire is slipped on to the felly-band and the locking-ring 19 is then adjusted in position. This locking-ring has the bayonet-joint slots 20, which 80 are adapted to engage the studs 3 on the felly-band, and when said bayonet-joint slots have been brought into engagement with the studs 3, the locking-ring 19 is 85 turned to complete the joint. To allow for this turning of the locking-ring without in any way interfering with the valve-opening 6, the locking-ring is provided with the recessed portion 21.

In order to lock the locking-plate in position and prevent its shifting so as to release the bayonet joint, I provide the locking-plate 22, which has the ratchet-teeth 23 adapted to engage the ratchet-teeth 24 95 of the plate 7. The locking-plate 22 is provided with the slots 25, which are adapted to engage the threaded pins 8, said slots 25 providing for a certain amount of adjustment of the plate 22 in case the locking-ring 19 is not moved to its full extent; and, at the same time, permitting the lug 26 on said locking-plate to engage the notch 27 in the locking-ring 19. When the locking-plate 22 has been adjusted, the nuts 28 100 are applied to the projecting screws 8 which hold the locking-plate in position.

In order to remove the tire-rim, the nuts 28 are first unscrewed and the locking-plate 22 removed. By means of the instrument 29, 110 illustrated in Fig. 8, the locking-ring 19 is then shifted. This instrument has the piv-

oted cross-bar 30 with the openings 31, which engage the threaded pins 8. The inner end 32 of the instrument is slightly pointed and fits into the recess 33 in the locking-ring. By moving the lever 29, the locking-ring is shifted so as to release the slots 20 from the studs 3 whereupon the ring can be withdrawn. After the locking-ring is withdrawn, it is a simple matter to re- move the tire-rim 5, and the sections of the tire-rim are separated by removing the screw 14 and the block 13, whereby the spring-ring 10 collapses and the tire sections can be readily separated to release the tire. In re- assembling the parts, the reverse of what has just been described takes place and the assembling can be done rapidly and with very little labor.

By my invention, I provide a simple form of detachable rim, which only requires the removal of two nuts and the shifting of the locking-ring to bring about a separation of the parts for the removal of the tire-rim.

Another feature of advantage in my construction is the locking-plate, which holds the locking-ring in position, said locking- plate being so arranged as to provide for the locking even though the ring may not be turned to its full extent, which under some conditions, may not be always possible.

What I claim is:

1. In a detachable rim for vehicle-wheels, the combination with the felly, of a felly-

band, a tire-rim, a locking-ring interposed between the felly-band and the said tire-rim, 33 a bayonet joint connection between said ring and said felly-band, a vertical ratchet-plate on said felly, a removable locking-plate having ratchet-teeth engaging the teeth of said ratchet-plate, a projection on said locking-plate engaging a recess formed in said locking-ring, and means for securing said locking-plate in position.

2. In a detachable rim for vehicle-wheels, the combination with the felly, of a felly- 45 band, a tire-rim engaging said band, a locking-ring interposed between said felly-band and said tire-rim, a bayonet-joint connec- tion between said locking-ring and said felly-band, a vertical ratchet-plate on said felly, threaded pins on said ratchet-plate, a locking plate having ratchet-teeth adapted to engage the teeth of said ratchet-plate, said locking-plate having slots in the ends there- 50 of engaging said pins, a projection on said locking-plate adapted to engage a recess formed in said locking-ring, and securing means on said pins for holding said locking-plate in position.

In testimony whereof, I the said GEORGE 60 H. S. MOYES, have hereunto set my hand.

GEORGE H. S. MOYES.
